REFRIGERATING APPARATUS

Lawrence A. Philipp, Detroit, Mich., assignor to
Nash-Kelvinator Corporation, Detroit, Mich.,
a corporation of Maryland

Application December 10, 1942, Serial No. 468,487

8 Claims. (Cl. 62—89)

1

This invention relates to refrigerating apparatus.

One of the objects of my invention is to provide an improved arrangement in a multiple temperature refrigerator for maintaining the cabinet insulation free of moisture.

Another object of my invention is to provide in a refrigerator a low temperature evaporator and a relatively high temperature evaporator, which higher temperature evaporator is located adjacent the insulation of the refrigerator, and to arrange said insulation in such a manner that there is a space for water vapor diffusion from moisture collected on said high temperature evaporator to said low temperature evaporator.

Further objects and advantages of the present invention will be apparent from the following description, reference being had to the accompanying drawings, wherein a preferred form of the present invention is clearly shown.

In the drawings:

Fig. 1 is a view in elevation and partly broken away of a refrigerator embodying features of my invention;

Fig. 2 is a view taken along line 2—2 of Fig. 1;

Fig. 3 is a view taken along the line 3—3 of Fig. 1;

Fig. 4 is a view taken along the line 4—4 of Fig. 2;

Fig. 5 is a view taken along the line 5—5 of Fig. 2; and

Fig. 6 is a fragmentary view in perspective showing a channel member embodying features of my invention.

Referring to the drawings, the numeral 20 designates, in general, a refrigerator cabinet having an inner metallic liner 22 and an outer metallic casing 24. Interposed between the inner liner 22 and the outer casing 24 is insulation 27. The inner liner 22 forms walls of food storage compartment 30. In the lower portion of the cabinet is provided a machine compartment 32. The front part of the food storage compartment is closed by door 33 and the front part of the machine compartment 32 is closed by door 34 which carries a movable vegetable bin 35.

The refrigerator herein disclosed is of the multiple temperature type and includes an ice making evaporator 36 of a primary refrigerating system positioned in the food storage compartment 30, and also includes a relatively high temperature evaporator 38 which forms a part of a secondary refrigerating system. The evapo-

2

rator 38 is secured to the exterior wall of the liner 22 and extends across a portion of the rear wall and the bottom wall of the liner. The evaporator 38 is utilized for cooling a portion of the food storage compartment 30 by absorbing heat through the walls of the liner. The evaporator 36 is positioned in the upper portion of the food storage compartment and is utilized for freezing substances and for cooling circulating air in the upper portion of the food storage compartment 30.

Located in the machine compartment 32 is a refrigerant condensing unit 40. The condensing unit includes a motor compressor unit 42 which compresses refrigerant and delivers it to a condenser 46 wherein it is liquified and from which it is delivered to the evaporator 36 through a small diameter conduit 50. This small diameter conduit 50 controls the flow of refrigerant flowing to evaporator 36 by metering the correct amount of liquid refrigerant. Evaporated refrigerant is withdrawn from evaporator 36 to the condensing unit through conduit 51.

In addition to the evaporators 36 and 38, a third evaporator 52 is provided for condensing evaporated refrigerant from the evaporator 38. The evaporator 52 is positioned in the insulation between the inner casing and outer casing and is coiled about a tank 54, which tank is connected to the evaporator 38 in such a manner that both ends of the evaporator 38 are in open communication with the interior of the tank 54. Liquid refrigerant passing through the small diameter conduit 50 first passes to the evaporator 52 where it is in good heat exchange relation with the tank 54 to condense any evaporated refrigerant contained in the tank 54. The liquid refrigerant then passes through evaporator 52 into conduit 60 whence it flows into the primary evaporator 36. Preferably, the evaporator 36 is of the so-called flooded type and operates below the freezing point of water during operation of the condensing unit. The high temperature evaporator 38 is utilized for cooling the lower portion of the food storage compartment through the walls of the liner, and preferably this evaporator operates at a temperature above the freezing point of water at least part of the time.

Within the food storage compartment there are provided glass shelves 64, 66 and 68. These shelves are horizontally positioned in the food storage compartment and extend from the front of the cabinet to a point adjacent the rear wall of the liner. As will be noted, the shelves are slightly spaced from the rear wall of the liner

so as to permit a slight circulation of air along the rear wall of the liner above and below the glass shelves. Adjacent the front part of the food storage compartment and at the lower portion thereof, I have provided glass doors 72, which doors cooperate with the bottom wall of the liner and glass shelf 66 to provide for enclosing a high humidity compartment which is refrigerated by evaporator 38.

Any suitable form of insulation may be utilized between the inner liner and outer casing, such, for example, as cork herein shown, or other well known insulating materials, such, for example, as corrugated paper, "rock wool" or other fibrous material, as desired.

In refrigerators of the type herein disclosed wherein liner cooling is employed, there is a tendency to collect moisture on the refrigerant evaporators positioned between the inner liner and outer casing and on the exterior walls of the lining member, and in the absence of some provisions for disposing of such moisture the insulation becomes wetted and loses its insulating qualities. In order to overcome this objection, I have provided in the insulation immediately below the bottom wall of the liner, channels 78 and in the insulation extending up the rear wall of the liner I have provided channels 80. These channels are adjacent the evaporator 38 and each channel 80 is in open communication with a channel 78. Also, in the upper portion of the cabinet I have provided metallic channel members 82 which are in open communication with the channels 80. These metallic channel members are utilized in connection with insulation, herein denoted as 86, as the insulation 86 is adapted to be removed from the cabinet in the event it is desired to remove the evaporator 36 therefrom. In such case it may be desirable to utilize insulation at this particular place of the type which may be loose fibrous material since it may be readily removed and inserted about the channel members 82 and the evaporator 52. A removable panel 90 is provided at the rear of the insulation 86 and an opening 92 is provided in the liner 22. This opening will permit the removal of the evaporator 36 through the rear wall of the cabinet without disconnecting the refrigerant conduits associated therewith. The opening 92 is partially closed by cover panel 98, which is secured to the liner 22 by studs 100. It is noted that this cover panel 98 is spaced from the inner liner 22 so as to allow a passage 99 between the food storage compartment and the insulation on the exterior of the side of the liner 22. It will also be noted that the opening 92 is adjacent the channel members 82 whereby a passageway is provided from the interior of the food storage compartment through the space 99 between the liner 22 and cover plate 98 and through the spaces provided by channel members 82 and channels 80 and 78. Consequently, there is a complete passage open between the evaporator 38 and the evaporator 36. By this arrangement water vapor diffusion in air permits the moisture collecting on the rear side of a liner member and on the evaporator 38 to move by diffusion through the passageways 78, 80 and 99 and into the interior of the food storage compartment where the moisture contacts the low temperature evaporator 36 and is frozen out thereon. Thus, moisture does not collect between the inner liner and outer casing to such an extent that the insulation would become wetted and lose its insulating characteristics. In actual test of such an arrangement,

it has been found that insulation as originally installed in the refrigerator contains some moisture and after a period of operation in a refrigerator, as herein disclosed, the actual moisture content of the insulation was less than when originally inserted in the refrigerator. It will, therefore, be noted that in my improved refrigerator the insulation remains dry although multiple temperatures are maintained and liner cooling forms a part of the refrigerator.

Further details of the cabinet construction and refrigerant primary and secondary systems herein disclosed and the operation of said systems, together with the air flow in the cabinet, are more specifically described in my Patent No. 2,361,792, issued October 31, 1944, for Refrigerating apparatus, of which the present application is an improvement and has provisions for venting the insulation between the high and low temperature evaporators whereby moisture is allowed to diffuse in the air and pass to the low temperature evaporator.

Although only a preferred form of the invention has been illustrated, and that form described in detail, it will be apparent to those skilled in the art that various modifications may be made therein without departing from the spirit of the invention or from the scope of the appended claims.

I claim:

1. Refrigerating apparatus comprising a cabinet having an inner liner and an outer casing, insulation between said liner and casing, said liner forming walls of a food storage compartment, a refrigerant evaporator positioned in said food compartment and being adapted to operate at a relatively low temperature, and a refrigerant evaporator positioned on the exterior surface of said liner and being adapted to operate at a relatively high temperature and above the freezing point of water at least part of the time, said insulation being spaced from said evaporator positioned on said liner and said liner having an opening in a wall thereof communicating with the space between the insulation and liner to establish a communication path between said evaporators to allow for water vapor diffusion in air from the moisture collected on the relatively high temperature evaporator to flow to the relatively low temperature evaporator.

2. Refrigerating apparatus comprising a cabinet having an inner liner and an outer casing, insulation between said liner and casing, said liner forming walls of a food storage compartment, a refrigerant evaporator positioned in said food compartment and being adapted to operate at a relatively low temperature, and a refrigerant evaporator positioned on the exterior surface of said liner and being adapted to operate at a relatively high temperature and above the freezing point of water at least part of the time, said insulation being channelled adjacent said evaporator positioned on said liner and said liner having an opening in a wall thereof communicating with the channelled space between the insulation and liner to establish a communication path between said evaporators to allow for water vapor diffusion in air from the moisture collected on the relatively high temperature evaporator to flow to the relatively low temperature evaporator.

3. Refrigerating apparatus comprising a cabinet, a liner for said cabinet, said liner having an opening, a relatively low temperature evaporator positioned in said cabinet on the interior side of

said liner, a relatively high temperature evaporator positioned in said cabinet on the opposite side of said liner, and insulation positioned in said cabinet adjacent said high temperature evaporator, said high temperature evaporator being adapted to operate above the freezing point of water at least a portion of the time and being so positioned as to condense out moisture from the air contacting said insulation and high temperature evaporator and said insulation including a channel to provide with said liner opening a vent for water vapor diffusion in air from moisture collected on the relatively high temperature evaporator so that said moisture may flow to the relatively low temperature evaporator.

4. Refrigerating apparatus comprising a cabinet having a liner forming walls of a food storage compartment and having an opening, a refrigerant evaporator positioned in heat exchange relation with an exterior surface of said liner, a relatively low temperature evaporator in said food storage compartment of said cabinet and insulation channelled to allow a vent along said exterior surface of said liner to said opening to provide a path for the passage of vapor from one evaporator to the other.

5. Refrigerating apparatus comprising a cabinet having a liner forming walls of the food storage compartment and having an opening, a refrigerant evaporator secured to the exterior rear surface of said liner, a relatively cold refrigerant evaporator positioned in said food compartment of said cabinet, and insulation positioned adjacent said exterior rear surface of said liner and being provided with a channelled portion to allow a passageway to said opening to provide a path for the passage of vapor from one evaporator to the other.

6. Refrigerating apparatus comprising a cabi-

net having a liner forming walls of a food compartment and having an opening, a refrigerant evaporator secured to the exterior rear and bottom wall of said liner, a relatively low temperature evaporator positioned in said food compartment of said cabinet, and insulation positioned adjacent said rear and bottom walls of said liner on the exterior side of said liner and being provided with a channelled portion to provide a passageway to said opening to provide a path for the passage of vapor from one evaporator to the other.

7. Refrigerating apparatus comprising a cabinet having a liner forming walls of a food storage compartment, a refrigerant evaporator secured to the exterior rear and bottom walls of said liner, a relatively low temperature evaporator positioned in said cabinet in the interior of said liner in said compartment, said liner being provided with an opening in its rear wall, and insulation positioned on the exterior of said liner adjacent said rear and bottom walls and being channelled along the rear and bottom walls to provide a passageway to said opening and between said evaporators.

8. Refrigerating apparatus comprising a cabinet having a liner forming walls of a food storage compartment, a secondary refrigerant evaporator secured to the exterior rear and bottom walls of said liner, a relatively low temperature primary refrigerant evaporator positioned in said food storage compartment of said cabinet, said liner being provided with an opening, an insulation positioned on the exterior side of said liner adjacent said rear and bottom walls of said liner and being provided with a channelled portion to provide a passageway to said opening to provide a communication path between said evaporators.

LAWRENCE A. PHILIPP.
